SWIMMING DEVICE

Filed Sept. 16, 1921. 3 Sheets-Sheet 3

UNITED STATES PATENT OFFICE.

ALEXANDER B. KUPSCHE, OF CHICAGO, ILLINOIS.

SWIMMING DEVICE.

Application filed September 16, 1921. Serial No. 501,165.

To all whom it may concern:

Be it known that I, ALEXANDER B. KUPSCHE, a citizen of Latvia, and a resident of Chicago, county of Cook, and State of Illinois, have invented certain new and useful Improvements in Swimming Devices, of which the following is a specification.

My invention relates generally to improvements in apparatus for facilitating movement through the water, and has particular reference to improvements in devices which shall sustain the user as well as facilitate movement through the water, and hence serve as a life saving device.

15 The general object of my invention is to provide apparatus which can be folded into a compact space for storage and which can be quickly and easily made ready for use.

20 A further object of my invention is to provide apparatus of the character described which may be safely used by any person whether such person can swim or not, and which shall have means for propelling the same through the water; and it is a further 25 object of my invention to provide a device of this character, which can be very quickly adapted for use by a person that desires to swim and whereby greater speed can be secured.

30 A further object of my invention is to provide a device of the above character which shall be composed of relatively few parts and which shall be safe and durable in construction.

35 My invention consists generally in the form, arrangement, construction and co-operation of the parts whereby the above named objects, together with others that will appear hereinafter, are attainable; and my 40 invention will be more readily understood by reference to the accompanying drawings, which illustrate, what I consider, at the present time, to be the preferred embodiment thereof.

45 In said drawings:

Fig. 1 is a view of the device indicating the manner in which it is ordinarily used by a person unable to swim.

Fig. 2 illustrates the manner in which 50 the device is ordinarily used by one who is able to swim.

Fig. 3 is a side elevation of the device, the full line position of the parts being that shown in Fig. 2, and the dotted line position

of the parts indicating other positions in which certain of the parts may be placed.

Fig. 4 is a detail view partly in section and partly in elevation illustrating the construction of the lower middle part of the U-shaped buoyant part of the apparatus.

Fig. 5 is a detail sectional view of the propeller construction.

Fig. 6 is a face view of one of the propeller blades.

Fig. 7 is a face view of the propellers in the position that they occupy when the device is in use.

Fig. 8 is a detail view, on an enlarged scale, viewed substantially along the line 8—8 of Fig. 1.

Fig. 9 is a detail sectional view, substantially on the line 9—9 of Fig. 8, the stabilizing board, however, being shown in its inoperative position.

Fig. 10 is a detail sectional view of the crank and gear mechanism for operating the propeller shaft.

Fig. 11 is a view substantially along the line 11—11 of Fig. 10.

Fig. 12 is a detail view illustrating the mechanism for locking the propeller shaft in the two positions shown in Figs. 1 and 2; and

Fig. 13 is a detail view illustrating the construction of the pedals.

The device may be used merely for pleasure in swimming, but it is especially designed for use as a part of a life-saving equipment of a vessel and it is, therefore, provided with many novel features adapting it particularly to use. Thus it is so designed that the parts may be all readily folded or positioned in such manner that it occupies substantially little, if any more space, than is required for an ordinary-sized circular life preserver of the usual construction. And yet, it may be quickly adapted for use not only as a mere device to sustain a person in the water, but also to enable very rapid movement through the water and hence enable the person more easily and certainly to make his way to a place of safety.

The device, as here shown, is composed of a substantially U-shaped member 1 which is composed of some relatively light material, such for example, as cork. As here shown, it is composed of a plurality of lay-

ers of cork 2, which are threaded upon a metal tube 3. The metal tube 3 serves to add the necessary rigidity to the structure and, still being made of thin walled tubing, adds 5 but little weight to the structure.

Mounted or secured to the lower part of the U-shaped structure is a metal band or sleeve 4 which is secured in place by suitable straps 5. The sleeve 4 is countersunk, 10 as indicated at 6, and in the countersunk portion I mount another sleeve 7 which sleeve is provided with a slidable bolt 8. The sleeve 7 may be rotated on the sleeve 4 and may be locked in either of two diametrically opposite positions by the bolt 8 engaging with recesses provided in the lugs 9 and 10, respectively. Secured firmly in a boss 11 of the sleeve 7 is a brace or tube 12 which at its outer end is firmly attached to 20 a frame or yoke member 13 in which the cross-shaft 14 is mounted for rotation. To the outer ends of the cross-shaft 14 there is affixed the cranks 15 and 16, respectively, having swingably secured thereto the pedals 25 17 and 18. These pedals are of novel construction in that they contain a loop or band 19 which is composed of some relatively light material, such as cork, and which, therefore, serves to position the pedals in the 30 water so that the feet of the user may be very readily inserted.

Positioned within the frame 13 is a frame 20 which serves to support a propeller shaft 21, the propeller shaft being rotatably 35 mounted at one end in the block 22 and at the other end in the wall 23 of the frame 20. The propeller shaft 21 carries a bevel gear 24 at one end, which meshes with the bevel gear 25 that is fixed to rotate with the 40 shaft 14. Thus when the shaft 14 is rotated, by virtue of the user pedaling the device, rotary movement is imparted to the propeller shaft 21.

At the outer end of the propeller shaft a 45 propeller of novel construction is affixed. The propeller, in this instance, is composed of three separate independent blades 26, 27 and 28, provided with hub portions having openings adapted to receive the end 21' of 50 the propeller shaft. They are mounted for free rotation thereon. The extreme end portion of the propeller shaft 21 is threaded and just inwardly thereof the shaft is squared as indicated at 21'', and on this 55 squared portion a washer 29 is mounted. It is held in place by means of the nut 30. Thus, the washer rotates with the propeller shaft 21. Also mounted on the propeller shaft for sliding movement is a sleeve 31, 60 normally pressed toward the washer 29 by means of a spring 32. The sleeve 31 is provided with two pins 33 which are adapted to enter openings provided in the washer 29 and in the hub portions of the propeller blades 26, 27 and 28. Thus, by retract- 65

ing the hub 31 the pins 33, may be withdrawn from the propeller blades and the blades can then be all rotated to a single position such as is shown by means of dotted lines in Fig. 3. This is the position that they occupy when not in use and when the device, as a whole, is collapsed for storage. To position the propeller blades for use, it is but necessary to swing them around the propeller shaft 21' and as soon as they reach their proper positions the pins 33 enter into place, thus operatively connecting the propeller blades to the propeller shaft. It will be understood that the hubs of the propeller blades are provided with openings that are so spaced, relative to each other, that the three propeller blades will be spaced 120 degrees apart.

For locking the frame 20 and the propeller shaft 21, which it carries, in either of the two positions shown by means of full lines in Figs. 1 and 2 the latch mechanism, best shown in Figs. 10, 11 and 12, is provided. This latch mechanism comprises a block 34 which is slidable upon the shaft 20 45, being normally pressed against the frame 20 by means of the spring 35. The block 34 is provided with two spaced pins 36 and 37 which are adapted to enter either the two diametrically opposite openings 38 or the two openings 39 in the hub portion 50 of the yoke 13. To swing the frame 20 from one position to the other it is necessary to retract the pins 36 and 37 and in order that this may be conveniently accomplished 55 I have provided the foot or treadle lever 40 which is pivoted on the frame 20 for swinging movement, and which is attached at the other end to the yoke 41 that is pivotally mounted in the block 34 on the pivot members 42 and 43 respectively. The connections between member 40 and members 20 and 41 is relatively loose to permit the necessary swinging movement. The end portions 41' of the yoke 41 form cam surfaces 60 so that when the yoke 41 is swung toward the element 25, see Fig. 12, the block 34 is moved longitudinally of the shaft and the pins 36 and 37 withdrawn from the openings 65 in the hub portion of the yoke 13. A piece of strap metal extends between the ends of the yoke 41 to form a bearing for the spring 35. Thus, the entire frame 20 with the propeller shaft and propeller attached thereto, 70 can be swung from the position that it occupies to a position at right angles thereto. For example, it can be swung from the full line position shown in Fig. 3 to the dotted line position shown in that figure. When it reaches its new position it is automatically 75 locked into place because the pins 36 and 37 are pressed into place by means of the spring 35. The manner in which the device is ordinarily used by a non-swimmer is 80 indicated in Fig. 1, wherein it will be ob- 85

served that the device occupies, as a whole, a vertical position, the user being seated in the U-shaped member 1, which because of its buoyancy serves to support the user.

5 By operating the cranks 15 and 16, rotary movement is imparted to the propeller which, obviously, propels the device through the water. The propelling action may be assisted to any desired extent by 10 the user manipulating his arms after the manner of swimming. Assuming the device to be operated in the manner shown in Fig. 1, it is obvious that the propeller tending to move the lower part of the device forward 15 would tend to swing the upper part downward, thus unbalancing the user and destroying the effectiveness of the device, as a lifesaver. To counteract this tendency, the stabilizing board 44 is provided. This is 20 made of wood or some other material that will float and is swingably attached to the portion 1 of the device, by means of the yoke 45 and the pivot pin 46. Thus when not in use, this board simply swings downwardly 25 into a position close to the side of the device 1, but when placed in the water swings upwardly to the position shown in Fig. 1, thus effectively overcoming any tendency that the propeller may have to swing or over-balance 30 the device. Actual use has shown the effectiveness of the apparatus and that it may be safely manipulated in the condition shown in Fig. 1. In this position, however, movement through the water is relatively 35 slow, due to the fact that not only must the resistance of the device be overcome, but the resistance that the whole length of the body offers.

For one that can swim the device is preferably used in the manner shown in Fig. 2, 40 the propeller being swung into line with the supporting tube or shaft 12 and there locked, as before described. The user still straddles the device 1, but assumes a position in the 45 water such as is normally assumed by a person in swimming, that is to say assumes a position but slightly inclined to the horizontal in which position but little resistance to the forward movement is interposed. 50 When used in this manner the stabilizing board 44 does not function, sufficient stability being given to the device by the swimmer himself.

In describing the details of construction, 55 I neglected to state that a spring 47 is provided for the purpose of swinging the propeller shaft and its supporting frame to the right angular position shown in Fig. 1 when the locking pins have been removed, as before described, thus enabling the complete 60 foot operation of this change.

While the device serves admirably for life saving purposes, it also makes a device that

can be used to good advantage in water sports.

I claim:—

1. A device of the class described embodying therein, a buoyant element, a propeller mechanism, a support extending between the propeller mechanism and the buoyant element, means swingably joining the propeller mechanism and said support, means for locking said propeller mechanism in different angular positions, said means including a shaft, an element slidable thereon, and mutually interlocking pins and recesses on the propeller mechanism and said slidable element.

2. A device of the class described embodying therein, a buoyant element, a propeller mechanism, a support extending between the propeller mechanism and the buoyant element, means swingably joining the propeller mechanism and said support, means for locking said propeller mechanism in different angular positions, said means including a shaft, an element slidable thereon, and mutually interlocking pins, and recesses on the propeller mechanism and said slidable element, and a foot lever connected to operate said slidable element.

3. A device of the class described embodying therein a buoyant element, a propeller mechanism carried thereby, and cranks for operating said propeller mechanism, said cranks having pedals fitted with buoyant straps.

4. A device of the class described embodying therein, a U-shaped buoyant element, a propeller mechanism, a support extending between the propeller mechanism and the buoyant element, means swingably joining the propeller mechanism and said support, means for locking said propeller mechanism in different angular positions, said means including a shaft, an element slidable thereon, and mutually interlocking pins and recesses on the propeller mechanism and said slidable element.

5. A device of the class described embodying therein, a U-shaped buoyant element, a propeller mechanism, a support extending between the propeller mechanism and the buoyant element, means swingably joining the propeller mechanism and said support, means for locking said propeller mechanism in different angular positions, said means including a shaft, an element slidable thereon, and mutually interlocking pins, recesses on the propeller mechanism and said slidable element, and a foot lever connected to operate said slidable element.

In testimony whereof, I have hereunto set my hand, this 23 day of August, 1921.

ALEXANDER B. KUPSCHE.
